UNITED STATES PATENT OFFICE.

GEORGE E. WITHERELL, OF HARTFORD, CONNECTICUT, ASSIGNOR TO
REMINGTON ARMS COMPANY, OF ILION, NEW YORK, A CORPORA-
TION OF NEW YORK.

SINGLE-TRIGGER MECHANISM FOR FIREARMS.

SPECIFICATION forming part of Letters Patent No. 767,537, dated August 18, 1904.

Application filed May 27, 1902. Serial No. 109,252. (No model.)

To all whom it may concern:

Be it known that I, GEORGE E. WITHERELL, a citizen of the United States, and a resident of Hartford, in the county of Hartford and 5 State of Connecticut, have invented certain new and useful Improvements in Firing Mechanism for Firearms, of which the following is a specification.

My invention relates to that class of firearms in which a plural number of hammers and sears are employed and in which a plural number of hammers may be released by the 10 operation of a single trigger; and the objects, among others, are to provide means for preventing involuntary discharge of the firearm and also to simplify the coupling mechanism between the sears.

One form of device by the use of which these objects may be attained is illustrated in 15 the accompanying drawings, in which—

Figure 1 is a plan view of the breech and of a portion of the stock of a double-barrel, shotgun with parts broken away to show construction and with the gun broken down. 20 Fig. 2 is a side view of the same with parts broken away to show construction. Fig. 3 is a detail top plan view showing the relative position of the sears, couplers, and interceptor-slide after the discharge of the right-hand barrel and with the hammer of the left-hand 25 barrel cocked. Fig. 4 is a like view, but showing the position of these parts at the instant of discharge of the right-hand barrel. Fig. 5 is a detail side view of the sears, coupler, interceptor-slide, and a portion of a hammer and illustrating a normal position of the parts after the release of the hammer from the sear. Fig. 6 is a detail view showing the 30 preferred form of means for maintaining the sear in the same vertical position whether the hammer be up or down.

While my invention is applicable to any form of firearm in which a plural number of sears is employed and whether operated by a 35 single trigger or a plural number of triggers, I have chosen a double-barrel shotgun with a plural number of triggers as the preferred

form of gun in connection with which to illustrate my invention; but I do not wish to be understood as limiting myself and do not 50 limit myself to the invention disclosed herein solely in connection with a gun of the form herein shown.

In the accompanying drawings the numeral 1 denotes the stock, 2 the barrel, 3 the fore end, and 4 the frame, of the gun, to which the barrel is pivoted in the ordinary manner. The gun is also provided with cocking-levers 5 and hammers 6. All of the parts above mentioned may be of any well-known and 55 ordinary form, as they form no part of the present invention except as to detailed construction of the hammer. The gun is also provided with the customary parts usual in devices of this character, as the operating-springs, release-lever, safety appliances, &c.

The hammer 6 is pivotally mounted in the frame in the usual manner and is provided on its under surface with a notch 7 for engagement with the end of the sear 9. The hammer is also 60 provided with a cam projection 8, that operates in connection with the sear, as will be hereinafter described.

The sear 9 is pivotally mounted in the frame with its forward end projecting in position to 75 engage the notch 7 in the hammer. The tail 10 has formed therein a recess 11, made by overturning the end of the sear-tail.

A coupler 12 is pivotally mounted on the sear, preferably near its front end, and has 80 at its front end a coupler-cam 13, formed, preferably, on an upward-projecting part from the coupler, this coupler-cam cooperating with the cam projection 8 from the hammer to cause the coupler to be swung on its pivot 85 on the sear. The coupler has at its rear end a lateral projection or nose which lies and has a lateral movement within the recess 11 of the sear-tail. A stop-pin 15 is also located on the coupler and by engagement with the over-turned part of the sear-tail limits the inward-swinging movement of the forward end of the coupler. A spring 16 is secured to the side of the sear with its end pressing against the

coupler at a point preferably adjacent to the point of pivotal connection of the coupler with the sear.

The parts above described as to cocking-lever, hammer, sear, and parts borne thereon have been described with reference to a single barrel of the gun, and it is understood that these parts are duplicated in the gun—that is, a like set of parts used appurtenant to each barrel—except that the arrangement of the parts is altered to such extent only as to make it applicable to the barrel in connection with which it is used, and like reference characters are used in the drawings herein to denote the parts appurtenant to both the right and the left hand barrels.

A forward trigger 17 is pivotally mounted in the trigger-plate 19 appurtenant to the firing mechanism of the right-hand barrel, and a rearward trigger 18 is also pivotally mounted in said trigger-plate and appurtenant to the firing mechanism of the left-hand barrel. Each of these triggers is adapted to engage the under surface of the sear appurtenant thereto and to raise said sear when the trigger is pulled backward.

The means for preventing the accidental discharge of the gun includes an interceptor-slide 20, mounted in a slideway 21. In the preferred form of the device and as illustrated herein these slideways are formed in the safety supporting-stud 22, the interceptor-slide straddling said stud and having side pieces 23 located in the slideways on opposite sides of the safety supporting - stud. These side pieces have at their forward end guides 24, that project into grooves 25 in opposite sides of the projection 26 from the trigger-plate. The rear end 27 of the interceptor-slide is enlarged to a considerable extent for the purpose of providing sufficient weight to cause the slide to move against the force of the interceptor-spring 28. This interceptor-spring is located on a guide-pin 29, projecting forward from the guide-pin support 30, secured to the trigger-plate. This guide-pin projects into the interceptor-slide and serves as a means of guiding the latter when the guides 24 are located outside of the grooves 25.

An interceptor 31 is located on the end of a projection from the forward end of the interceptor-slide. As shown in the drawings, this interceptor is located between the sear-tails 55 10 and in position to be interposed between the noses 14 on the couplers when the interceptor-slide is located at the rearward limit of its play.

The usual safety appliances consisting of the safety-slide 32, rocker 33, and thumb-slide 34 are employed; but a more detailed description of this is deemed unnecessary herein.

It is to be noted that a peculiar feature of the coupling device herein resides in the fact that the coupler on each of the sears is en-

gaged with the opposite sear only when the hammer appurtenant to a given coupler is down and the hammer appurtenant to the opposite coupler is raised or cocked—that is, with both of the hammers in a normal position, raised or lowered, each coupler is disengaged from the opposite sear and each sear is free to act independently of the opposite sear. It will be obvious that when both barrels have been fired the couplers may assume any position, as they will be caused to assume proper position as the hammers are thrown back and the gun cocked. The noses of the couplers are suitably beveled, as shown, to allow the interceptor to be freely interposed 75 between the noses and also to allow the nose of each coupler to engage in the recess of the opposite sear with either of the sears in any position. By this construction I am also enabled to make the couplers practically counterparts each of the other, except, of course, one must be arranged for a right and the other for a left hand sear. The couplers are of the same length, and the noses of the couplers are located opposite each other. This simplifies the construction both of the couplers and of the sears.

The operation of the device is as follows: Both hammers being down, the barrel is released by means of the top lever and the gun 95 broken down, as shown in Figs. 1 and 2 of the drawings. In this operation the hammers are thrown backward by means of the cocking-levers 5 and the sears 9 each engage with the notches 7 on each of the hammers. 100 As the hammers are thrown backward the cam projections 8 coming in contact with the coupler-cams 13 swing the rear ends of the couplers outward, so that the recess 11 in each of the sears is free to receive the nose of the 105 coupler from the opposite sear. The normal position of the interceptor-slide during this operation and, in fact, at all times except at the instant immediately following the discharge of the gun is at the forward limit of 110 its play, as shown in Figs. 1, 2, 3, and 5 of the drawings. In this position the interceptor 31 is located immediately in front of the noses 14 of the couplers. The right-hand trigger being now pulled, the sear appurtenant to the right-hand barrel is raised, freeing it from the notch 7 on the hammer and allowing the latter to be thrown forward under the force of its spring. This operation 115 discharges the right - hand barrel, and the force of the discharge causes the gun in its recoil to be forced against the shoulder of the user. From the natural tendency of the user to resist this recoil and the spring action of the shoulder the gun is immediately thrown 120 forward in what is known as the "counter-recoil." This counter-recoil causes the gun to move independent of the interceptor-slide—that is, the latter being of considerable weight and free to move in its slideways does not re- 125 130

spond to said force as quickly as the gun, and the latter is therefore forced forward independent of the interceptor-slide. This causes the interceptor 31 to be interposed between the 5 noses of the couplers, so that neither is moved under the influence of the coupler-springs 16. Immediately after the counter-recoil the interceptor-slide 20 is forced forward to its normal position by means of the interceptor-springs 28 freeing the interceptor from its position between the couplers and allowing the coupler of the right-hand barrel to swing into the recess in the sear appurtenant to the left-hand barrel. It will be noted that a pull of 15 either the right or left hand trigger will discharge the other barrel of the gun.

The above description will apply equally well to the operation of the gun by pulling the free or left-hand trigger and discharging the left-hand barrel first, it being necessary to substitute in said description the terms "left" for "right" and "right" for "left" wherever used.

A fault has been found in devices of this 25 class prior to my invention from the fact that when a barrel is discharged the coupler immediately acts to unite the two sears. This being accomplished before the counter-recoil acts and before pressure of the finger on the 30 trigger has been released, the counter-recoil forces the gun and trigger against the finger and immediately discharges the opposite barrel. By the use of the interceptor herein described it will be noted that this coupling operation cannot take place until after the counter-recoil, and therefore all danger of immediately discharging the opposite barrel is overcome.

It is to be noted that by the peculiar arrangement and construction of the interceptor-slide and the interceptor the gun may be held in any position without affecting the operation of the interceptor to perform its function.

45 A sear-stop 35 (see Fig. 2) is located underneath the rear end of the sear and serves to hold the sear in such position that the couplers will surely engage the recess in the opposite sear whether the hammer is up or down, 50 except when raised in the movement of a trigger to discharge the gun. There is a stop appurtenant to each sear. The sears are thus always maintained in the same vertical position, so that the coupler on one sear may readily engage the opposite sear. In the preferred 55 form of means for preserving this vertical position of the sear, as shown in Fig. 6, the hammer is so constructed that the portion of the sear in engagement with the hammer shall be 60 always maintained at the same distance from the center of the pivot on which the hammer swings—that is, the point 36 on the hammer at which the sear touches when the hammer is down is the same distance from the center 65 of the pivot of the hammer as the point 37 ad-

jacent to the notch 7 with which the sear engages when the hammer is up or cocked.

What I claim as my invention, and desire to secure by Letters Patent, is—

1. In a multibarrel firearm having a plural 70 number of hammers and a plural number of sears with their appurtenant parts, a coupler to connect said sears, an elastically-actuated device to prevent operation of the coupler, and means for moving the sears.

2. In a multibarrel firearm having a plural 75 number of hammers and a plural number of sears with their appurtenant parts, a plural number of couplers adapted to connect two sears, a device operated by the movement of 80 the gun actuated by discharge to prevent the operation of said couplers, and means for moving the sears.

3. In a double-barrel firearm having a hammer and a sear with their appurtenant parts 85 appurtenant to each barrel, a coupler mounted on each sear to engage the opposite sear, an elastically-actuated device to prevent operation of the coupler, and means for moving said sears.

4. In a multibarrel firearm having a plural 90 number of hammers and a plural number of sears with their appurtenant parts, a coupler to connect said sears, an interceptor, means for actuating the interceptor to interpose it in 95 the path of the movement of the coupler, and means for moving the sears.

5. In a multibarrel firearm having a plural 100 number of hammers and a plural number of sears with their appurtenant parts, a coupler to connect said sears, an interceptor temporarily 105 interposed in the path of movement of the coupler, and means for moving the sears.

6. In a multibarrel firearm having a plural 110 number of hammers and a plural number of sears with their appurtenant parts, a coupler to connect said sears, an interceptor-slide mounted in operative relation to said coupler, an interceptor secured to the slide to be temporarily interposed in the path of movement 115 of the coupler, and means for moving the sears.

7. In a double-barrel firearm having a hammer and a sear with their appurtenant parts appurtenant to each barrel, a coupler mounted on each sear to engage the opposite sear, 120 an interceptor temporarily interposed in the path of movement of said coupler, and means for moving the sears.

8. In a double-barrel firearm having a hammer and a sear with their appurtenant parts 125 appurtenant to each barrel, a coupler mounted on each sear to engage the opposite sear, an interceptor-slide mounted in operative relation to the couplers, an interceptor connected to the slide and temporarily interposed in the path of movement of the couplers, and means for moving the sears.

9. In a multibarrel firearm having a plural 130 number of hammers and a plural number of sears with their appurtenant parts, a coupler

to connect said sears, a slide mounted appurtenant to said coupler and moved by the recoil of the firearm, an interceptor secured to the slide, means for restoring the slide, and 5 means for moving the sears.

10. In a double-barrel firearm having a hammer and a sear with their appurtenant parts appurtenant to each barrel, a coupler mounted on each sear to engage the opposite sear, a slide 10 mounted in operative relation to the couplers to be moved by the recoil of the firearm, an interceptor secured to said slide temporarily interposed in the path of movement of said couplers, means for restoring the slide, and 15 means for moving the sears.

11. In a double-barrel firearm having a hammer and a sear with their appurtenant parts appurtenant to each barrel, a coupler mounted on each sear and having a beveled nose 20 adapted to engage the opposite sear, a slide mounted with respect to said couplers and moved by the recoil of the firearm, an interceptor secured to the slide and by its movement interposed in the path of movement of 25 the couplers, means for restoring the slide, and means for moving the sears.

12. In a double-barrel firearm having a hammer and a sear with their appurtenant parts appurtenant to each barrel and a recess in each 30 sear, a coupler mounted on each sear, each coupler having a nose oppositely disposed to the nose on and to engage a recess in the other coupler, means for operating the couplers, and a trigger appurtenant to each sear.

35. 13. In a double-barrel firearm having a hammer and a sear with their appurtenant parts appurtenant to each barrel and a recess in each sear, a coupler pivoted on each sear and having a beveled nose oppositely disposed to 40 the nose on the other coupler, means for operating the couplers, a spring-actuated slide mounted with respect to the sears and moved by the recoil of the firearm, an interceptor

secured to the slide to be interposed between the couplers, and a trigger appurtenant to 45 each sear.

14. In a double-barrel firearm having a hammer and a sear with their appurtenant parts appurtenant to each barrel and a recess in each sear, a coupler mounted to swing on each 50 sear, a nose on each coupler normally disengaged from the opposite sear, means for swinging the coupler, and a trigger appurtenant to each sear.

15. In a firearm having a plural number of 55 barrels, hammers and sears with their appurtenant parts, said sears having recesses for the reception of the noses of the couplers, a coupler pivoted on each sear to engage a recess in the opposite sear, a stop appurtenant 60 to each sear to maintain them in the same vertical position whether the hammers be raised or lowered, and means for raising the sears.

16. In a firearm having a plural number of 65 barrels, a sear appurtenant to each barrel, a coupler pivoted on a sear to engage the opposite sear, a hammer appurtenant to each barrel and having two points of engagement with the sear, when the hammer is raised and 70 lowered, at the same distance from the center of the pivot of the hammer, and means for raising the sears.

17. In a firearm having a plural number of 75 barrels, a sear appurtenant to each barrel each sear having an oppositely-disposed recess, a coupler pivoted on each sear to engage the recess in the opposite sear, means for raising the sears, and a hammer appurtenant 80 to each barrel, each hammer having two points of contact with the sear both located at the same distance from the pivot of the hammer.
